1.7 : Bottom

1.8 : Perspective

The design concerns a sole for a sports shoe and is characterized in particular by H-shaped patterns on the toe and on the sides of the lateral band of the sole and by the shapes of the raised elements on the underside of the sole; in the front part of the underside of the sole among the raised elements there is an essentially H-shaped reinforcement; the rear part of the bottom surface of the sole has an H-shaped element in relief; all said elements in relief have patterns comprising oblique Hs arranged in parallel lines; the front and rear parts of the bottom surface of the sole are separated by a contrasting-color transverse band.
